UNITED STATES PATENT OFFICE

CLAUDE C. CALKINS, OF SPOKANE, WASHINGTON

SHOE BEARING

Application filed December 7, 1929. Serial No. 412,436.

My present invention relates to improvements in shoe bearings for that class or type of agricultural machinery in which the shoe is designed to support in properly aligned 5 journals and bearings, a rotative member or rod. This rod must be submerged below the surface of the ground and be retained in that position largely by the aid of said shoes, when this shoe and a series of others, each 10 supporting the rotating rod, are advanced through the soil.

Rotary rod weeders of the general type utilizing a sub-surface rotating rod for engaging weeds or other plant growth to remove them by the roots and deposit them 15 on the surface of the ground, have come into quite extensive use in many parts of the agricultural districts and are an important adjunct in preparing seed beds or maintaining ground in a fallow state.

In my present invention it is an object to provide in combination, a shoe and bearing co-operating with a revolving rod in such a manner that the journal shall be free to 25 rotate beneath the surface of the soil with a minimum of friction with the soil, and without accumulating grit or dirt in such excess in the moving parts as to seriously interfere with the rotative action, or cause 30 undue wear in the several parts comprising the unitary structure.

It is another object of my invention to provide replaceable parts so that when an old part becomes worn, a new one may be 25 substituted in a simple and efficient manner.

It is a further object of my invention to provide in a shoe means for maintaining the shoe beneath the surface of the soil so that as the rotative rod is drawn forward 40 through the soil, the shoes, which are at spaced intervals thereon shall assist in holding the rod to its work at a depth of several inches below the surface of the soil.

In its more detailed nature the invention 45 comprises certain novel features of construction, combination, and arrangement of parts, all of which will be first fully described and then be specifically pointed out in the appended claims and illustrated in the accompanying drawings in which:—

Figure 1 is a fragmentary rod weeder showing the shoe carrying the rotative rod in its approximate position in the ground when it is in use.

Figure 2 is a front elevation of the shoe. 55

Figure 3 is a perspective of the shoe, a supporting gooseneck being indicated in part thereon and also the rotative rod.

Figure 4 is a cross-sectional view taken 60 on line 4—4 of Figure 2.

Figure 5 is a vertical cross-section through the center of the bearings of the shoe as at line 5—5 of Figure 4.

Figure 6 is a plan view of the removable bearing member. 65

Figure 7 is a side view thereof.

The invention comprises a shoe with a body portion 10 having a side socket 11 receiving the end of a gooseneck, and the shoe is fastened to the gooseneck through the 70 expedient of suitable bolts 13 and 13' and nuts 14 and 14'.

One of the bearings is shown in the shoe in advance of the terminal of the gooseneck a part 15 of which is formed integral with 75 the shoe and a complementary part 16 forms a removable member or bearing portion that is held clamped by means of a lip or tongue 17 between the terminal end 18 of the gooseneck and the sidewall of the shoe. 80

In advance of the bearing, the shoe terminates in a downwardly inclined and forwardly extending nose or point 19 with a sharp front edge 20 and a flaring bottom constituting a runner. This plow-pointed 85 structure with its sharp forward edge 20 and a gradually thickening lower portion has a tendency to aid the point in entering the ground and also to maintain the rod, which it supports, in proper relation beneath the surface of the soil. 90

It is usual in rotary rod weeders to have four or five of these supporting shoes each carried by a gooseneck supported by and below frame 21 of the weeder proper. This 95 supporting arrangement of the rod aids in aligning the rotatable rod or shaft 22, which preferably is square in cross-section and which rotates in a counter-clockwise direction with respect to its showing in Figure 100

1 and Figure 3. This directional movement aids to a certain extent in keeping the rod under the surface and also in pulling out the weeds by the roots as they fold backward over the advancing rod.

The shoe at its top is formed with a downwardly extending nose, and an integral, lateral lip 23 on the nose engages over a flange 24 of the journal bushing 26 and 10 the lip serves to deflect the soil from the keeper 25 of the removable bearing portion 16 and protects the same from undue wear and pressure.

At intervals on the rod 22 corresponding 15 with the spacing of the shoes, are located the journal bushings or circular members 26 and these journal bushings have a central bore to correspond with the cross-sectional shape of the rod. The journal bushings 20 26 are fashioned with annular flanges as 24 and are designed to fit loosely into the bearing sections 15 and 16.

The stationary bearing section 15 which 25 comprises the forward half of the bearing and which is integral with the shoe is made comparatively narrow, as 27 so that a recess 28 is formed on either side of the bearing providing room to receive the flanged journal 26. The width of the shoe in advance 30 of the journal is sufficient to deflect the earth or soil through which the shoe is passing so that little or none of the soil will enter the bearing proper.

It is desirable to make this bearing as 35 frictionless as possible and since it must operate underground it is also desirable to have it as loose and self-cleaning as possible.

Since the thrust of the rod journal is imposed against the rear, removable bearing member 16, I make this member of extreme 40 width, that is, equal to the width of the journal bushing 26, and in this member is provided with an arcuate groove 29 to receive the flange 24 of the journal member 45 so that the removable bearing member or section forming the rear half of the bearing assembly, not only takes the thrust and receives the wear of the journal, but it also acts as a keeper for this journal bushing 26 50 to prevent longitudinal movement thereof.

The removable bearing section 16 is retained by its lip 17, which fits in a recess 30 in the sidewall of the shoe and is clamped in place by the gooseneck and shoe when 55 they are assembled, one of the bolts 13 securing the gooseneck at its terminal end 18 to the shoe and passing through a notch 32 cut in the end of the lip 17.

The removable and replaceable bearing 60 section 16 fits into the socket 11 formed in the shoe as described, and to insure proper adjustment of the section a flange 33 is provided on the section. The upper face 34 of the flange is tapered to correspond with 65 a similar taper in the shoe so that the bear-

ing section is aligned with respect to the shoe and also to the revolving journal 24 so as to create a minimum of friction.

At 35 the end of the removable bearing member 16 is tapered somewhat and the stationary section 15 of the bearing is also tapered to provide plenty of room for the dirt or grit to leave the bearing by falling therefrom.

It is essential for sub-surface bearings of 70 this type that they be extremely loose and have a free-fitting so as not to allow soil to pack between the rotating and the non-rotating parts for the reason that such packing would seriously increase the power required for rotative movement of the rod.

It is also necessary to have a minimum 75 of bearing surface on the forward half of the bearing and for this purpose the bearing is cut back as much as possible as best shown in Figure 4 and thus providing very little opportunity for the dirt to pack.

From the foregoing description, taken in connection with the accompanying drawings, it is thought the complete structure, 80 operation and advantages of my invention will be readily understood by those skilled in the art.

What I claim is:

1. A shoe bearing of the character described comprising a body member having a forwardly projecting and downwardly inclined nose, a bearing formed partly integral with the body member and partly of a removable section aligned therein, a rotatable flanged journal member in said bearing, a recess on one side of the body member to receive the flange of the journal member, a lip integral with the body member to engage over the flange, and means upon the removable bearing member to prevent lateral displacement of the rotatable journal.

2. In a shoe bearing, a shoe member, a socket on the rear thereof for attachment to a gooseneck, a replaceable bearing member having a tongue, and means in said socket for receiving said tongue, a forwardly projecting plow-shaped nose on said shoe member, an integral bearing portion therein cooperating with the replaceable bearing member, a depression on one side of the shoe member for receiving the flange of a loosely fitting rotatable journal member, a lip on the upward forward portion of the shoe member integral therewith and engaging over the flange of the rotatable member, of a means upon the replaceable bearing for engaging the flange of the rotatable journal to prevent longitudinal displacement of the flanged member.

3. A bearing of the character described comprising a shoe and a bearing portion integral therewith and presenting a narrow bearing surface to a journal member, of a removable bearing portion supported and

retained in the shoe, and presenting a wide bearing surface to a journal member, and a rotatable journal member co-operating therewith.

5 4. The combination with a support, of a shoe having a fixed bearing section, a complementary removable bearing section and means for clamping said section between the support and shoe, a rotatable journal-bushing mounted in said sections, a retaining flange on said bushing, and co-acting means on said sections for the flange.

10 5. A bearing as described comprising a shoe having a forwardly projecting and downwardly inclined nose on its forward end, said shoe having a rear socket and a support fitted in the socket, bolts for fastening the shoe to the socket, a forward bearing section integral with the shoe, a rear removable bearing section having a rear notched tongue between the shoe and support and secured by one of said bolts, a journal-bushing rotatable in the bearing-sections, and means for retaining said bushing against lateral displacement relative to said bearing sections.

15 6. A bearing as described comprising a shoe having a rear, lateral socket and a support fitted in the socket, bolts fastening the shoe to the support, a forward bearing section integral with the shoe, a rear removable bearing section, an anchoring tongue on the removable section and means for securing said tongue between the shoe and support, a journal-bushing rotatable in the bearing sections, an exterior annular flange on the bushing, and said rear section having a retaining groove for said flange.

In testimony whereof I affix my signature.

40 CLAUDE C. CALKINS.
